CLAIM

The ornamental design for a sealing element for a vehicle canopy, as shown and described.

DESCRIPTION

FIG. 1 illustrates a top perspective view of a sealing element for a vehicle canopy according to the present disclosure;

FIG. 2 illustrates a bottom perspective view thereof;

FIG. 3 illustrates a left side view thereof;

FIG. 4 illustrates a right side view thereof;

FIG. 5 illustrates a rear side view thereof;

FIG. 6 illustrates a front side view thereof;

FIG. 7 illustrates a top side view thereof; and,

FIG. 8 illustrates a bottom side view thereof.

In the drawings, any broken lines illustrate portions of the sealing element for a vehicle canopy that form no part of the claimed design.

1 Claim, 5 Drawing Sheets
